UNITED STATES PATENT OFFICE.

CHARLES A. BINDHAMMER, OF CHICAGO, ILLINOIS.

SIGN.

1,163,638.

Specification of Letters Patent. Patented Dec. 14, 1915.

Application filed November 2, 1914. Serial No. 869,836.

To all whom it may concern:

Be it known that I, CHARLES A. BINDHAMMER, a citizen of the United States, residing at Chicago, in the county of Cook and State of Illinois, have invented certain new and useful Improvements in Signs, of which the following is a specification.

My invention relates to improvements in signs and has especial reference to that type known as interchangeable, display signs.

One of the objects of my invention is to generally improve their appearance and convenience of manipulation and to enhance the economy of construction of such devices.

A more specific object is to provide means whereupon removable letters may be supported and arranged in parallel rows, and coöperating means on the letters, whereby they may be easily located and held in proper alinement without requiring tedious time-consuming adjustment, on the part of the operator, and which said means will hold the letters in their true relative positions irrespective of the bodily movement or dis- placement of the sign structure.

Still another object of my invention is to make the individual, letter holding and positioning means, as an integral part of the letter and to utilize the letter supporting means for holding the letters in flat contact with the back plate of the sign in front of which the letters are to be mounted.

Other and further objects of my invention will become readily apparent to persons skilled in the art from a consideration of the following description when taken in conjunction with the drawings, wherein—

Figure 1 shows a front elevation of my sign and sign supporting means. Fig. 2 is an end elevation of the same. Fig. 3 is a broken away portion of the sign showing the letter supporting wires and means for tightening them. Fig. 4 is a front elevation of one of my letters showing the integral attaching and positioning means. Fig. 5 is a transverse section of said letter taken on line 5—5 of Fig. 4.

In all the views the same reference characters are employed to indicate similar parts.

In the construction of my sign I prefer to provide a frame 10 in which I mount a plate 11. This back plate is preferably translucent or transparent and is properly held in the frame. Across the front, or face of the plate 11, I place parallel letter-supporting wires 13 and 14 upon which to

mount the letters. The parts 13 and 14 are two limbs of the same wire; the limb 13 passing through a perforation of the frame, as at 15, and downwardly, as at 16, into a similar perforation 17, thence continuing, as the wire 14, to the opposite side of the frame. Each limb of the wire is provided with a screw threaded stem 18, which is connected with the wire, and a screw threaded sleeve 19, coöperating therewith having a head 20 resting upon the outer surface of the frame member 21. The tension of the wires 13 and 14 may be adjusted by these devices in an obvious manner. When the tensions of the wires 13 and 14 are properly adjusted they lie substantially parallel with the front face of the back plate 11 and almost in contact therewith.

A typical letter, of the kind used in connection with my sign, is shown in Fig. 4 in which tongues 22 are pushed laterally at one end out of the body part of the letter to overlie the supporting wire. Each tongue is provided with a slightly kinked portion 23 or stop 23 to provide a contacting surface, corresponding in contour with the rounded edge of the wire, thereby to stop and hold the letter in a predetermined position with reference to the wire. As a supplemental means, or as an additional stop for holding the letter in vertical position with reference to the wire, I provide indentations 24 and 25 on opposite sides of the wire preferably on opposite side edges of the letter, and a sufficient distance apart to admit the wire between them.

In placing the letters on the supporting wires of the signs, as shown in Fig. 1, the letter is first inserted back of the wire, and then pressed downwardly until the wire passes over the lower indentations 25, at which time the operator will feel the snap action when the wire is between the upper and lower stops and the spring tongue 22 will clamp over the wire and hold it in position, between the two stops or indentations, thereby assuring the operator of the fact that the letter is in vertical position. The kink or stop 23, made in the tongue 22, will perform substantially the same function, independently of the indentations, but if desired both devices may be employed in the same letter or either device may be employed without the other or a single stop may be used on each side of the tongue and above the wire as an abutment against which the wire

- impinges when the letter is pressed into position. After the letters have been placed upon the supporting wire, in the manner described, they, or any of them, may be moved 5 longitudinally on the wire to any selected position and the friction of the tongue 22 with the wire, is sufficient to prevent accidental longitudinal displacement of the letter. The attaching means being located on 10 the front of the letter the overlying supporting wire operates to hold the letter in close contact with the front surface of the back plate 11, so that when one or more lamps 26, are placed back of a luminous plate, a sharp 15 outline will be defined by the edges of the letter being in intimate contact with the translucent or transparent backing plate and no apparent distortion or shadow of the letter will be visible by the observer.
- 19 I prefer to mount, on the back of my sign, a housing 27 inclosing one or more lamps 26, and having its inner surface polished so as to reflect the light produced by the lamp, through the translucent or transparent backing plate 11, and I also prefer to have this 25 housing completely closed and extending from end to end of the sign and to place therein one or more lamps, the number to be determined by the brilliancy of the light and 30 the length of the sign.
- As a convenient means for supporting the sign I provide a base plate 28 having two vertically extending curved arms 29 rising therefrom, each arm provided with an eye 35 30 for attachment of a suspending chain 31. The chains 31—31 being fastened to the upper surface of the sign frame 21 as at 32. While this is a convenient means for suspending and supporting my signs, it is not 40 necessary or essential to its use and operation and while I have shown a transparent or translucent backing plate, through which the light may shine, to clearly outline the

letter, this feature of my sign is not essential to its use and operation, as a completely 45 opaque plate may be employed and the lamp to illuminate the plate may be entirely dispensed with.

The letters are preferably made of thin sheet metal and the holding tongues and protuberances may be punched or indented in the body part of the letters and I prefer to place two such tongues and accompanying protuberances on each letter, where it is convenient to do so.

To remove the letters from the supporting wires it is only necessary to seize the top of the letter and hold the supporting part of the wire and raise the letter up until the tongue with its letter is moved from its contact with the wire.

Having described my invention, what I claim is:—

1. A sign comprising a wire; a letter to be mounted on the wire; a tongue comprising 65 an integral part of the letter, on the front thereof to overlie the wire; and stops adjacent the opposite side edges of the letter in the path of the wire to hold the letter in a predetermined vertical position with respect 70 to the wire.

2. A sign comprising a wire; a letter to be mounted on the wire; a tongue cut from the body part of the letter but remaining a part thereof to overlie the wire for frictional 75 engagement therewith; and a projection formed on the body part of the letter adjacent each of the opposite side edges to provide positioning stops for the wire.

In testimony whereof I hereunto set my 80 hand in the presence of two subscribing witnesses.

CHARLES A. BINDHAMMER.

In the presence of—
STANLEY W. COOK,
MARY F. ALLEN.
